(57) **CLAIM**

The ornamental design for a knife, as shown and described.

DESCRIPTION

FIG. 1 is a side elevation view of a knife showing the new design;

FIG. 2 is a side elevation of a first alternate configuration thereof wherein the blade portion of the knife is fully rotated to show the other end of the blade portion;

FIG. 3 is a side elevation view of a second alternate configuration thereof wherein the blade portion of the knife is partially rotated to show both ends of the blade portion of the knife;

FIG. 4 is a front elevation view thereof;

FIG. 5 is a rear elevation view thereof;

FIG. 6 is a top plan view thereof; and,

FIG. 7 is a bottom plan view thereof.

The broken lines in FIGS. 1–3 are directed to a feature of the knife that forms no part of the claim.

The side of the knife not shown is identical to the side that is shown.
